US0D1078104S

(12) **United States Design Patent** (10) **Patent No.:** **US D1,078,104 S**
Su et al. (45) **Date of Patent:** **** Jun. 3, 2025**

(54) **EXTRUSION**

(71) Applicant: **NINGBO HELONG NEW MATERIAL CO., LTD.**, Ningbo (CN)
(72) Inventors: **Zhenju Su**, Zhejiang (CN); **Hailong Liu**, Zhejiang (CN); **Yuhan Liao**, Zhejiang (CN); **Yong Zhang**, Zhejiang (CN); **Diqing Yao**, Zhejiang (CN); **Jian Zou**, Zhejiang (CN); **Hongbin Xu**, Zhejiang (CN)

(**) Term: **15 Years**

(21) Appl. No.: **35/520,559**

(22) Filed: **Feb. 28, 2024**

(80) **Hague Agreement Data**

Int. Filing Date: **Feb. 28, 2024**
Int. Reg. No.: **DM/236121**
Int. Reg. Date: **Feb. 28, 2024**
Int. Reg. Pub. Date: **Apr. 12, 2024**

(30) **Foreign Application Priority Data**

Aug. 28, 2023 (CN) 202330551587.5

(51) **LOC (15) Cl.** **25-01**

(52) **U.S. Cl.**

USPC **D25/122**; D25/128

Primary Examiner — Leanne Was-Englehart

(57) **CLAIM**

The ornamental design for an extrusion as shown and described.

DESCRIPTION

1. Extrusion

1.1 : Front

1.2 : Left

1.3 : Top

1.4 : Perspective

1 Claim, 4 Drawing Sheets
